(57) **CLAIM**

The ornamental design for an insulated grommet for end post buckles, as shown and described.

DESCRIPTION

FIG. 1 is a front perspective view of an insulated grommet for end post buckles showing my new design;
 FIG. 2 is a top perspective view thereof;
 FIG. 3 is a bottom perspective view thereof;
 FIG. 4 is a top view thereof;
 FIG. 5 is a bottom view thereof;
 FIG. 6 is a front side view thereof, the front side view being identical to the side view from any other direction;
 FIG. 7 is a top perspective view thereof, the grommet being secured to a first attaching buckle; and,
 FIG. 8 is a side perspective view thereof, the grommet being secured to a second attaching buckle.
 The attaching buckles shown in broken lines in FIGS. 7 and 8 are included for environmental purposes only, and form no part of the claimed design.
